BILLFOLD

Joseph C. Davio, Agawam, Mass.

Application March 24, 1939, Serial No. 263,843

6 Claims. (Cl. 150—38)

This invention relates to an improvement in flexible pocket receptacles adapted to carry bills, cards, and the like, and commonly known as bill folds.

An object of my invention is to provide a bill fold having improved means to compensate for the variation in the relative movement between the inner and the outer walls of the bill receiving compartment, whereby, when the bill fold is doubled or otherwise folded upon itself to fit the pocket, it will fold to substantially flat, compact form, even when a considerable number of bills are contained in said compartment, without buckling or causing irregular folding of the material particularly with respect to the inner wall of the said compartment.

Another object of my invention is to provide an improved bill fold having separate pockets, for cards and the like, and which can be made preferably from a single piece of flexible material that is folded and interlocked in folded relation, in an improved manner, and without stitching.

A further object of my invention is to provide such compensating means in a form which will readily permit the use thereof in bill folds of different styles and designs.

Further objects and advantages of my invention will be more clearly understood from the following specification and from the accompanying drawings in which:

Figure 1 is a front view, in elevation, of a bill fold embodying my invention.

Figure 2 is a top plan view thereof.

Figure 3 is a flat plan view of a blank for said bill fold on a reduced scale.

Figure 4 is a top plan view on line 4—4 of Figure 1.

Figure 5 is a vertical view in section on line 5—5 of Figure 1.

Figure 6 is a plan view illustrating my improved bill fold when in folded position and containing a number of bills therein.

Figure 7 is a front view, in elevation, of a portion of my improved bill fold with parts broken away to show the construction thereof.

Figure 8 is a front plan view illustrating a different type of a bill fold embodying my invention.

Figure 9 is a flat plan view showing a portion of the blank illustrated in Figure 3, but with my invention applied thereto in a slightly modified form.

Figure 10 is a top plan view of the bill fold illustrated in Figure 8 showing the same in folded position.

In the embodiment of my invention as illus-

trated, my improved bill fold may be made up from a single piece of suitable sheet material 5, such as leather or the like, which is cut out in the form illustrated in Figure 3 and includes an outer wall section 10, and an inner wall section 11. The said outer wall section is provided with flaps 12 having extensions 13 connected thereto by connecting portions 14 which form slots 15 and notches 16 and 17 between the said extensions and flaps.

The wall sections 10 and 11 are disposed parallel to each other and spaced by intermediate sections 18, which are separated by an opening 19. Flaps 20 extend into said opening from each of the sections 18.

Each of the said sections 18 are also provided with an opening 21 which is pointed at the ends thereof, as at 22, to engage the edges of cards, which are disposed projecting through said opening, and prevent them from falling out of the bill fold.

The said sections 18 are also provided with tabs 23 that are cut through the material 5 and have extending ears 24 which adjoin openings 25 that receive the connecting portions 14.

If desired, a flap 26 may also be provided on the wall section 10, although this is not considered necessary.

It will be noted that the central portion of the wall section 11 is scored or otherwise provided with two parallel creases 11a, on the outer side thereof, and a similar crease 11b, on the inner side thereof, which will cause it to fold outwardly and form a "bellows fold" 27, as more clearly illustrated in Figure 6.

In folding the said bill fold from a blank, as illustrated in Figure 3, the sections 18 are first folded onto the section 10, on the dotted line 10a. The flaps 12, are then folded on the lines 12a, and the extensions 13 are then inserted through the slits 29 which form the tabs 22, and into the position clearly illustrated in Figures 1 and 7. The tabs 23 are then inserted through the slots 15 and said tabs are positioned in back of the connecting portions 14; thus the flaps 12 are interlocked, in the position illustrated in Figure 4, with the extensions 13 thereof flatly disposed between the sections 18 and the wall section 11.

The flaps 20, are then folded under the ends of the extensions 13, as clearly shown in Figure 4, to form pockets 30 which open through the slots 21 and separate pockets 31 between the said extension and wall 11.

The flap 26 is then folded inwardly to provide a finished edge for the outer wall section 10.

It will be noted that when the bill fold has been folded and completed to the form illustrated in Figure 1, the center portion of the wall section 11 will have a tendency to flex outwardly from the bill compartment 32, on account of the creases 11a and 11b provided by my invention.

It is commonly known that when a number of bills are to be contained in the pocket of a bill fold the inner wall of the bill compartment must be provided with means for taking up the variation in the length between the outer and inner walls when the bill fold is folded for inserting it in the pocket.

Heretofore, it has been customary to provide such means as a sliding inner wall for the bill compartment, or to provide various other arrangements, all of which have been found objectionable, particularly from the standpoint that they present considerable bulk to the bill fold when in folded position.

My invention permits the portion of the inner wall of the bill compartment, which is at the bend, to neatly fold outwardly and between the two sides of the bill fold, as clearly illustrated in Figure 6; thus permitting the said sides to come together in perfect alignment and without crowding or bulkiness at the bend of the bill fold. This will also permit orderly arrangement of the bills within the bill compartment and the papers in the pockets 30 and 31, which will not be disturbed when the bill fold is folded.

In the modification illustrated in Figure 8, the bill fold shown is of a type which is folded into three sections. My invention may be applied to this type of a bill fold in the same manner as to the two section type of bill fold illustrated in Figure 1 of the drawings.

It will be noted, from Figure 10, that the "bellows fold" provided by my invention will fold outwardly from the bill compartment and adjust itself to the spacing between the side sections of the bill fold. Therefore, when my invention is used in a three section bill fold, as illustrated in Figure 10, one of the "bellows folds" will only partly fold outwardly from the bill compartment as clearly shown at 33.

In the modifications shown in Figure 9, the blank for the bill fold is cut away as at 34, and a separate piece 35 is preferably cemented to the wall section 11 or secured thereto by other suitable means. This will permit a finished appearance to the "bellows fold" which would otherwise require a special operation due to the fact that the material of the blank is inverted, when the wall section 11 is folded over, and the unfinished side, such as common in leather, would show through between the intermediate sections 18.

It will also be noted, more clearly from Figure 7, that the ears 24, on the tabs 23, will rest in back of the connecting portions 14, thus securely interlocking the flaps 12 with the sections 18 and in position to cover the slits 29 so that a finished appearance is presented to the completed bill fold without the use of stitching or other means of securing the various sections together.

While I have described my invention in the embodiments illustrated, it is to be understood that the same may be used in various types of flexible containers, other than bill folds, without departing from the scope of my invention as set forth in the following claims.

I claim:

1. In a bill fold of the character described formed of a single piece of flexible material including an outer wall, an inner wall, supple-

mental sections adjacent to said inner wall, flaps on the said outer wall folded over the said inner wall and sections, extensions on said flaps extending through said sections disposed between said inner wall and sections and tabs on said sections engaging a portion connecting said flaps with said extensions and underlying said flaps.

2. A bill fold of the character described formed from a single piece of flexible material and comprising an outer wall, an inner wall, exteriorly disposed sections adjacent to said inner wall, flaps on said outer wall folded over said inner wall and overlying said sections, extensions on said flaps disposed between said sections and inner wall, tabs on said sections engaging a portion connecting said flaps with said extensions and interlocking with the said extensions for retaining the said bill fold in formed position, and flaps on said sections underlying the ends of said extensions to form pockets in said bill fold between the said extensions and sections; said sections having openings providing access to said pockets.

3. A bill fold constructed from a blank comprising a piece of flexible material adapted to be folded to provide a compartment, locking means for retaining said blank in folded condition comprising a slit shaped to form a tongue and locking tabs extending from said tongue within the extremities of a portion of said blank, a flap on another portion of said blank adapted to be inserted through said slit and having a slit therein adapted to receive said tongue in position wherein the said locking tabs engage a portion of said flap adjacent to the ends of the slit therein and thereby lock the same against withdrawal from the first mentioned slit to retain said blank in folded position.

4. A bill fold of the character described formed from a blank of flexible material having portions adapted to be folded to form said bill fold; said blank having a slit in a portion thereof shaped to form a tongue with tabs extending laterally therefrom, a flap on said blank having a slit therein and notches in the sides thereof; said flap being adapted to be inserted into the first mentioned slit with said notches locked against a portion of said blank adjacent to said slit and the slit in said flap being adapted to receive said tongue with the tabs therein in locked position against a portion of said flap adjacent to the slit therein.

5. A bill fold of the character described formed from a blank comprising an outer wall portion, an inner wall portion, an intermediate portion having an opening therein, flaps extending into said opening, said intermediate portion also having separate openings therein and slits forming tabs in said portion, ears extending from said tabs, flaps extending from said outer wall portion, extensions on said flaps connected thereto by means of connecting portions providing a slit between each of said extensions and flaps to receive the tabs in said intermediate portions, said extensions being disposable between said inner wall and intermediate portion and adapted to be secured to the first mentioned flaps to form pockets having entrances through openings in the intermediate portion, and creases on said inner wall portion for causing the same to fold towards one side thereof whereby when the said bill fold is completed from said blank, the said creases will render a portion of said inner wall foldable outwardly from said bill fold to permit adjustment of said inner wall upon the folding of said bill fold into two parallel sections.

6. A bill fold of the character described formed from a blank cut from a single piece of flexible material and comprising an outer wall, an inner wall having a portion adapted to be folded against the outer wall, and a plurality of transverse creases formed by score lines on said inner wall portion for causing an intermediate portion

thereof to fold outwardly upon the folding of said bill fold; said score lines including one at each side of said intermediate portion, on the outer surface thereof, and another score line on the inner surface of said portion facing the outer wall and centrally on said portion.

JOSEPH C. DAVIO.
